UNITED STATES PATENT OFFICE

2,478,620

SPACE HEATING SYSTEM

Thomas L. Arnold, West Hartford, Conn., assignor to The Vulcan Radiator Company, Hartford, Conn., a corporation of Connecticut

Application May 8, 1947, Serial No. 746,751

4 Claims. (Cl. 237—1)

1

This invention relates to space heating systems and more particularly to systems that are used for heating rooms in buildings.

An object of this invention is to provide a heating system which is economical to construct as well as highly efficient in its operation.

A further object of the invention is to provide such a heating system which may be used in dwellings and which may be installed at an extremely low cost so as to permit the use of an efficient hot water or steam heating system in low-priced dwellings.

A still further object of the invention is to provide an economical heating system which may be installed as a single unit system to heat a plurality of different rooms in a building, and which may be selectively controlled to provide a desired degree of heating in each room without the use of valves or the like and without effecting the heating of the other rooms which are heated by the same system.

Further objects and advantages of this invention will be more clearly understood from the following description and from the accompanying drawings in which:

Fig. 1 is a fragmentary plan view, illustrating my heating system as installed in a building.

Fig. 2 is a fragmentary side view, in vertical section, of said heating system.

Fig. 3 is a similar view illustrating the control of said system.

Fig. 4 is a view similar to Fig. 3 but illustrating the operation of the system when the heating element is disposed in a different position.

Fig. 5 is a similar view showing the heating element in another position.

As illustrated in the drawings, the numeral 5 denotes the walls at the corner of a building and the numeral 6 denotes the floor which is preferably constructed of a layer of cement 7 that may be supported upon a suitable foundation, as indicated at 8.

In order to permit the economical installation of a heating system which is particularly adapted for low-priced dwellings or other buildings, I provide in said floor a channel running along the exterior walls of the building and preferably at a distance of approximately one foot from said walls, since I have found, by exhaustive tests and research, that such a distance permits the most efficient operation of my novel heating system.

In the form shown, a suitable heating element, in the form of a radiator of conventional form, consists of a pipe 10 having a plurality of radiating fins 11 thereon. The said radiator is suit-

2

ably supported within the said channel 9 and may extend around a corner of the channel by the use of an elbow 12.

As illustrated in Figs. 1 to 3, the said radiator is placed adjacent to the wall 13 of the channel 9 which is nearest to the wall 5 of the building as I have also found that this further increases the efficiency of the heating system. If desired, suitable dampers 14 may be provided in the form of a strip which may be hinged, preferably to the wall of the channel farthest from the wall of the building, in such a manner that it may be retained in closed position as illustrated in Figs. 1 and 2 or dropped into open position as shown in Fig. 3. Separate dampers, such as 14, may be provided for each room in a dwelling in order to separately control the degree of heating for each individual room.

My invention is founded upon the well-known fact that air in a room will travel horizontally along the floor of the room and upwardly along the walls thereof. The provision of the heating radiator in the channel 9 will therefore cause said air to be heated as it passes over said channel in its movement toward the wall of the room. I have found that the most efficient operation may be obtained when the said radiator is placed adjacent to the wall of the channel which is nearest to the outer wall of the room, so as to permit the air currents to dip into said channel and then rise through the said radiator as it becomes heated thereby in its movement toward the wall of the room. I have further found that when the damper 14 is closed, as shown in Fig. 2, the air currents will travel toward the wall and become heated by the radiator but only to a degree of about 39% of the standard output of the particular radiator used. The most efficient operation of the system may be obtained when the damper 14 is open, as shown in Fig. 3. This will permit the air currents to dip downwardly into the channel 9 and then rise upwardly through the fins 11 of the radiator 10 and become heated thereby so that the space in the room will become heated by convection to a degree which has been proven to be approximately 85% of the standard output of the particular radiator used.

Exhaustive tests and research conducted on my invention have further proven that the heating efficiency of the radiator will become less as the said radiator is placed away from the wall 13 toward the opposite wall 15 of the channel 9. For instance, the tests have proven that, when the radiator is placed in the center of the channel, as shown in Fig. 4, a heating effi-

ciency of 74% of the standard output of the particular radiator used is obtained. Also, when the said radiator is placed adjacent the opposite wall 15, as shown in Fig. 5, an efficiency of 64% of the standard output of the particular radiator used is obtained. I have therefore established the correct position in which the radiator is to be placed within the groove 9 for rendering my invention operable for the highest degree of efficiency; the said position being illustrated in Figs. 1 to 3 in which position the flow of air through the radiator, as illustrated in Fig. 3, may be controlled by the use of a suitable damper, such as at 14, for selectively controlling the flow of the air through the radiator so that it will be heated to any desired degree between the 39% heating capacity, when the damper is closed, as shown in Fig. 2, and the 85% heating capacity, when the damper is open, as shown in Fig. 3.

It will be clearly understood from the above description that my improved heating system may be installed in a building by extending a single pipe along the outer walls of the building and through the adjoining rooms therein, which may be separated by suitable partitions, as indicated at 17, and that, by providing a separate damper in each room, the system may be adjusted for different degrees of heating in each room, independently of the adjoining rooms, by simply adjusting the damper 14 in the particular room or rooms wherein such adjustment is desired.

While no means has been shown in the drawings for adjusting the damper to different positions between the open and closed positions, the same may be readily provided by such as a chain and a suitable hook arrangement for receiving different links of the chain to regulate the position of the damper. Other forms of fastening means for the damper may be provided, if desired, and such may comprise a suitable arrangement by which the damper may be frictionally held in any adjusted position.

As illustrated in Fig. 1, a suitable grill 16 may be used to cover the heating system. This grill may be positioned flush with the floor in a suitable recess providing supporting shoulders for the grill along the edges of the channel 9 as clearly illustrated.

I claim:

1. For a building, a heating system of the character described comprising a heating radiator in the form of a pipe located within a channel below the plane of the floor of said building and running along and parallel with the walls thereof, the said pipe running adjacent said channel at one side thereof and along the wall of the channel nearest to the wall of the building, and means between said radiator and the wall of said channel spaced farthest from the radiator and substantially at floor level for controlling the flow of air relatively to the radiator as it moves along the floor toward the walls of said building and said channel being spaced a sufficient distance from the building wall whereby heated air may travel horizontally for a limited distance before contacting the building wall.

2. For a building, a heating system of the character described including a formation in the floor of said building providing a channel in said floor running along and adjacent to the outer walls of the building, a heating element in the form of a radiator located within said channel below the plane of said floor and running along and adjacent to the wall of said channel nearest to the walls of the building, the said radiator being spaced from the bottom of said channel and from the wall thereof farthest from the walls of the building, and means between the said radiator and the said farthest wall at substantially floor level for controlling the flow of air relatively to said radiator as it moves along said floor toward the said outer walls of the building.

3. For a building, a heating system comprising a radiator in the form of a pipe having a plurality of radiating fins thereon and located within a channel in the floor of said building and running along and adjacent to the outer walls of the building, the said radiator being supported adjacent to the wall of said channel nearest to the said walls of the building and above the bottom of the channel, a damper hingedly mounted upon the opposite wall of said channel adjacent its upper end and adjustable between said radiator and said opposite wall for controlling the degree to which air moving along said floor toward the outer walls of the building is permitted to dip into said channel and move through the fins of the radiator to thereby control the degree to which the said air is heated by the system.

4. For a building having a plurality of rooms, a heating system comprising a formation in the floor of said building providing a channel running continuously through separate rooms in said building and adjacent to an outer wall thereof, a heating element in the form of a radiator located within and running along said channel below the plane of the floor and adjacent to the wall of the channel nearest the building wall, and a separate damper in each of said separate rooms between the said radiator and the opposite wall of the channel and at substantially floor level for independently regulating the degree of heating in each room by controlling the flow of air entering the channel as it moves along the floor toward the said outer wall of the building in said room.
